DETOXICANT

Gustav J. Martin, Elmhurst, and Marvin R. Thompson, Great Neck, N. Y., assignors to William R. Warner & Company, Inc., New York, N. Y., a corporation of Delaware

No Drawing. Application May 2, 1940,
Serial No. 332,986

4 Claims. (Cl. 167—65)

This invention relates to therapeutic materials of lowered toxicity. More particularly, it relates to therapeutic agents comprising "Atophan" and similar compounds in admixture with a material lowering the toxicity thereof.

"Atophan" (phenylquinoline carboxylic acid) is a drug used in the treatment of rheumatism, gout and similar diseases of the human body. The amount of the drug that may be administered, however, is usually less than the amount that would obtain the maximum, or in many cases a desirable, therapeutic effect. This limit is occasioned by the toxic action of the "Atophan."

It is an object of our invention to provide a therapeutic agent comprising "Atophan," its related and similarly acting derivatives and compounds, such as novatophan, and atoquinol, which are non-toxic or of reduced toxicity and which can be administered in greater amounts in most cases, or at least in the usual amounts without an abjectionable toxic effect on the human being.

As is apparent from the above description, the drugs described have two characteristics, one therapeutic and the other toxic. It would be relatively simple to modify the drug or the action of the drug so as to alter its toxic as well as its therapeutic effect. However, it is not a simple matter to alter one of these characteristics without altering the other, i. e., to alter the toxicity without destroying the therapeutic effect.

The action and theory of detoxication has been appreciated heretofore, and in general, a detoxifying material is thought to combine or coat with the drug in the body in such a manner as to mask the toxic characteristic while leaving unaltered the structural characteristic of the compound that is responsible for the therapeutic effect. But the exact action of various materials is little known, and the nature of detoxicants or their action with a particular drug so as not to affect its therapeutic effect cannot be predicted from any available knowledge.

We have discovered that if cysteine or an equivalent compound is administered at the same time as the "Atophan" or related compound, the toxic properties of "Atophan" in the human system are eliminated or greatly reduced and minimized, but at the same time the therapeutic effect of the "Atophan" is not appreciably interfered with. The inclusion of ascorbic acid with the cysteine gives somewhat more effective results than cysteine alone or than ascorbic acid alone.

It is a further object of our invention therefore to provide a therapeutic agent comprising in

combination "Atophan" and related and similarly acting compounds and derivatives with cysteine and their equivalents, i. e., their precursors and biochemically related compounds.

5 In accordance with our invention, the "Atophan" or related compounds, may be admixed in the desired proportions with the cysteine or equivalent compounds or with the cysteine and ascorbic acid in either a dry mixture or in solution. This mixture may then be administered in the same way that "Atophan" is normally administered, namely, orally, parenterally, rectally, etc. While the cysteine alone or the cysteine and ascorbic acid may be administered to the human body separately from the "Atophan," we find it more convenient to administer them as a mixture since this assures that the proper amount of both ingredients will be administered at the same time, and also eliminates the necessity for administering two drugs which would be less convenient and might give rise to misunderstanding as to the amount and nature of the administration.

Upon being taken into the body, the "Atophan" or related compound and cysteine or the cysteine and ascorbic acid coat or react to produce a material having the non-toxic, therapeutic effect. If desired, the "Atophan" and ascorbic acid and/or cysteine may be reacted in the laboratory 15 in a manner similar to the action that takes place in the body in order to provide a single new compound which may be administered to produce the non-toxic therapeutic effect, the ascorbic acid conjugate having the approximate composition 20 $C_{22}H_{17}O_7N$, while the cysteine conjugate is represented by $C_{19}H_{18}O_4N_2S$. Both are hitherto unknown compounds.

The proportions of the materials are not critical, since both cysteine and ascorbic acid are 25 found in and formed from dietary components and may therefore be viewed as a food for the human body. They may be taken into the body in relatively large amounts without any harmful action. The upper limit of the proportion of 30 cysteine in our composition is therefore very high, although as a practical matter, in most instances, there is a maximum amount beyond which enhanced results are not obtained. Very small amounts of cysteine or cysteine and ascorbic acid 35 also obtain improved results, and there is no minimum below which some improvement is not obtained. The proportions may also vary somewhat, depending upon the tolerances and peculiarities of the patient with respect to the 40 "Atophan." In general, however, we find a mix-

ture comprising 1 to 10 parts of cysteine or cysteine and ascorbic acid in admixture with 5 parts of "Atophan" to be suitable in most instances. Preferably, the mixture comprises equal parts.

It will be apparent that we have provided therapeutic material having superior and advantageous non-toxic properties, as described in the specification and following claims forming a part thereof.

We claim:

1. A therapeutic agent for use in connection with the treatment of rheumatism, gout and similar ailments including "Atophan" for combating said ailments, in association with cysteine and an ascorbic acid to lower the toxicity of said "Atophan" without materially impairing the therapeutic effect thereof.

2. A therapeutic agent for use in connection with the treatment of rheumatism, gout and similar ailments including "Atophan" for combating said ailments, in association with cysteine to lower the toxicity of said "Atophan" without

materially impairing the therapeutic effect thereof.

3. A therapeutic agent for use in connection with the treatment of rheumatism, gout and similar ailments, comprising a compound selected from the group consisting of phenylcinchoninic acid and its esters, for combating said ailments, in association with cysteine and an ascorbic acid to lower the toxicity of said compound without materially impairing the therapeutic effect thereof.

4. A therapeutic agent for use in connection with the treatment of rheumatism, gout and similar ailments, comprising a compound selected from the group consisting of phenylcinchoninic acid and its esters, for combating said ailments, in association with cysteine to lower the toxicity of said compound without materially impairing the therapeutic effect thereof.
